FLUID-APPLYING MACHINE

Sidney J. Finn, Beverly, Mass., assignor to United Shoe Machinery Corporation, Paterson, N. J., a corporation of New Jersey

Application January 28, 1930, Serial No. 424,059

20 Claims. (Cl. 91—51)

This invention relates to fluid-applying machines and is illustrated herein as embodied in a machine for applying cement to the edges of the upper portions of shoes.

5 In the manufacture of shoes, machines for applying marginal stripes of cement to one or both sides of work-pieces are commonly used. In applying cement to work-pieces an important problem to be dealt with is the variation in the 10 absorptive character of the various shoe materials to be coated; the absorptive character of some materials tending to take up the applied cement and to carry it away from their attaching surfaces, thus leaving such surfaces, if not enough 15 cement is applied, insufficiently coated with cement, so that in subsequent assembling or folding operations there will be no firm adherence between the assembled or folded parts. Thus, it can be readily seen that work-pieces made up wholly 20 or in part of a textile material such, for example, as the canvas upper parts of shoes of the tennis or sneaker type and the soft cloth lining parts of overshoes, because of their absorptive character require the application of a stripe of 25 cement of greater thickness to their attaching surfaces than do those work-pieces made from a comparatively non-absorptive material such as leather. Accordingly, it is desirable, in machines 30 of the type referred to, in order to obviate the necessity of passing the work through the machine several times, to make provision for insuring that there will be deposited by one application of cement a stripe of cement of sufficient thickness 35 to cause the edges of the coated work-pieces to adhere firmly to their associated parts when assembled therewith regardless of the absorptive 40 character of the material coated. Furthermore, it is customary to provide shoe parts, such as those referred to above, with a stripe of cement of a width determined by the extent to which 45 the marginal portion of the work-piece to which the cement is to be applied is to overlap the part to which it is to be cemented, since on some parts a wider overlapping marginal portion is required than on others.

In view of the above, it is an object of the present invention to provide an improved fluid-applying machine by the use of which stripes of cement of ample thickness and of different widths 50 may be applied to the marginal portions of work-pieces, varying in absorptive character, by a single application.

One of the features of the invention resides in a novel recessed fluid carrying roll having deflecting 55 means associated therewith whereby the fluid

carried by the roll is deflected from the roll directly on to the work. In the illustrated embodiment of the invention a rotatable cement-carrying roll is constructed and arranged to carry a large quantity of cement in a recess by frictional drag. An inclined foot member is provided for engaging the cement carried by the roll and deflecting a sufficient quantity of the cement from the recess in the roll to the work. 60

Features of novelty are also to be recognized in the provision of applying members constructed and arranged for the carrying of a plurality of unusually thick ribbons of cement, together with the means for causing one or more of these ribbons to be applied to the work, thereby determining the width of a stripe of cement to be applied to the work. In the construction shown, foot members are provided having inclined ends which extend into the grooves of a cement-carrying roll between the roll and the work. The foot 65 members are independently adjustable relatively to the roll so that one or more of the ribbons of cement may be deflected from the roll to the work. Also, as illustrated, the spaced ends of an adjustable regulating member extend into 70 grooves formed in the cement-carrying roll to regulate the thicknesses of the ribbons of cement carried thereby. 75

It is a further very desirable characteristic of the machine herein shown that the deflecting 80 means may be adjusted relatively to the cement-carrying roll so that all of the cement carried by the roll will be deflected from the roll to the work; thus the roll may be kept clean and cement prevented from accumulating upon the cement-carrying surfaces thereof. 85 90

Preferably, and as illustrated, the cement-applying machine has oppositely disposed cement-applying devices adapted to apply stripes of cement of the required widths and thicknesses to the opposite marginal portions of a work-piece. In the illustrated embodiment of the invention, upper and lower cement-applying devices are provided, each comprising a sectional cement-carrying roll made up of a series of thin disks, 95 separated by hub members and forming a series of annular tracks or grooves for carrying an ample quantity of cement. Co-operating with each groove or track is an independently adjustable foot member, movable into and out of contact with the cement-carrying portion of each groove or track and arranged to deflect as much of the stripe of cement as is wanted from the roll to the edge of the work. 100 105

The above and other features of the invention 110

will now be more particularly described by reference to the accompanying drawing and will be pointed out in the claims.

In the drawing,

5 Fig. 1 is an end elevation of one embodiment of the invention with parts broken away to show more clearly the construction thereof;

Fig. 2 is a side elevation looking from the right in Fig. 1;

10 Fig. 3 is a perspective view of the lower cement-applying roll and some of its associated parts, some of the parts being in section for clearness of illustration; and

Fig. 4 is a view in perspective of the upper cement applying roll and its associated scraper.

The invention is herein illustrated as embodied in a machine of the type disclosed in United States Letters Patent No. 1,380,360, granted June 7, 1921, on application of J. W. Cosgrove, to which reference may be had for a description of parts not

fully shown or described.

Referring now particularly to Fig. 1, a novel upper fluid-carrying roll 10 is supported between the walls of a removable bracket 12 in the same manner as the fluid-applying roll of the patented machine, and receives cement from a tank 14 located at the top of and integral with the frame of the machine. This upper fluid-carrying roll 10 comprises a number of thin disks 16 separated

30 by hub members 18 the peripheral surfaces of which are smooth. The hub members 18 are smaller in diameter than the disks 16 and when assembled with the disks form a series of annular grooves or tracks 20, each having parallel side walls and a bottom wall disposed at right angles to the side walls and within the outer peripheries of the disks. In ways 22 in the upper edge of an upwardly inclined portion of the bracket 12 is a fluid-controlling slide or scraper

40 24, one end of which is slotted to form spaced projections 26 which extend into the grooves 20. The projections 26 are substantially as wide as the grooves 20 and their inner edges approach the downwardly traveling portions of the hub members 18. The outer end of the slide 24 has a flange 28 depending over the end wall of the bracket 12 and mounted for rotation in this flange is a screw 30 which may be turned by a head 32. The screw 30 is threaded into the end wall at 34

50 so that when it rotates it moves the slide 24 in its ways to vary the distance between the inner edges of the projections 26 and the downwardly traveling portions of the hub members 18, thereby determining the quantity of cement removed

55 from the tank 14 and carried by the tracks or grooves 20. As the roll 10 rotates, by means hereinafter described, a ribbon of cement of the desired thickness is carried in each track or groove 20 past the projections 26. The disks 16 are

60 near enough together to hold frictionally the ribbons of cement, thus opposing the tendency of the cement to drop out as it is carried toward the work by rotation of the roll 10. In order to cause the ribbons of cement carried by the grooves 20 to be applied to the work, each groove 20 is provided with an adjustable deflector or foot member 44. The plow-like deflectors 44 are provided with T-ends 46 inclined, as illustrated, and each end 46 has a sharpened upper edge portion 47. The ends 46 are substantially as wide as the grooves 20 and when moved into adjusted position, that is with their sharpened upper edges

47 in operative relation to the peripheries of the hub members 18, much of the cement carried by the grooves 20 will be pushed by the right side

of the T-ends 46, as seen in Fig. 1, out into contact with a marginal portion of the upper surface of the work as the work is fed past the applying point. If desired, the deflectors 44 may be adjusted so that their sharpened upper edges 47 will contact with the smooth peripheral surfaces of the hub members 18, thereby deflecting all of the cement from the grooves 20 directly on to the work. Thus the roll 10 may be cleaned and cement prevented from accumulating upon its cement-carrying surfaces. The deflectors 44 are supported between lugs 40 depending from a bracket 38 secured to the under side of the upwardly inclined portion of the bracket 12. A fulcrum screw 42 passes through the lugs 40 and the ends of the deflectors 44 and is threaded into the end wall 48 of the bracket 38, so that the deflectors 44 may be held in adjusted positions by tightening the screw 42.

The upper fluid-carrying roll 10 is rotated by means of a horizontal shaft 50 journaled in the frame of the machine and connected to the roll 10 by means of a key and slot connection 52, the roll 10 being centered upon the shaft 50 by an axial projection on the shaft (not shown) entering a bore in the middle of the roll 10.

Journaled in a carrier lever 58, similar to the carrier lever for the work-supporting roll of the Cosgrove patent, is a driven horizontal shaft 56 upon the forward end of which is mounted a lower fluid-carrying roll 54. The roll 54 is clamped against a shoulder on the shaft 56 by means of a nut 60 threaded upon a reduced end portion of the shaft. The shaft 56 is rotated by means of gears (not shown) at such a velocity that the adjacent portions of the rolls 10 and 54 move at the same peripheral speed. The lower fluid-carrying roll 54 may be lowered from co-operation with the upper fluid-carrying roll 10 in the same manner as the lower work-supporting roll of Patent No. 1,380,360 referred to above.

Secured by screws 62 to the outer end of the carrier lever 58 is a cement receptacle 64 partially surrounding the lower roll 54 and arranged to supply cement to the lower roll. A tank (not shown) of the barometric type may be used, if desired, to maintain the level of cement in the receptacle 64 through a conduit 66 fastened by means of bolts 70 to a flange 68 integral with the receptacle 64.

The lower fluid-carrying roll 54 is made up of a number of thin disks 72 separated by hub members 74 having smooth peripheral surfaces disposed at right angles to the opposite parallel sides of the disks 76, thus forming a series of annular grooves or tracks 76 for carrying fluid of a cementitious nature by frictional drag. Associated with the lower roll 54 is an adjustable fluid controller scraper 78 resting upon an inclined surface 84 of the receptacle 64 and held in adjusted position by a screw 86 threaded into the side wall of the receptacle 64 and passing through an inclined slot 88 parallel to the surface 84, said slot being formed in a downwardly projecting flange 90 of the scraper 78. Extending downwardly from the under side of a laterally extending portion 80 of the scraper 78 are spaced projections 82 substantially as wide as the grooves 76 and co-operating with opposite sides of the disks 72 and peripheries of the hub members 74 to control the quantity of cement carried by the grooves or tracks 76.

Furnished at 96 within the receptacle 64 and arranged to co-operate with the grooves 76 are adjustable deflectors 92, having ends 94 inclined

in a direction opposite to the inclined ends 46 of the upper deflectors 44. The lower edges 95 of the ends 94 are beveled to provide sharpened edge portions which, when moved into operative relation to the peripheries of the hub members 74, will engage the cement carried in the grooves 76 and cause the cement to be pushed out directly for the application to the lower surface of the work as the work is fed past the applying point. Adjustment of the deflectors 92 is effected by means of adjusting screws 98 threaded through the wall of the receptacle 64 and having their ends in engagement with downwardly projecting portions 100 of the deflectors 92. To enable the operator to clean the roll 54, the deflectors 92 may be adjusted to a position where their sharpened lower edges 95 contact with the smooth peripheral surfaces of the hub members 74, thereby deflecting all of the cement from the smooth peripheral surfaces of the hub members to the work. It will be seen from the foregoing that either the upper cement-applying device or the lower cement-applying device may be rendered ineffective to apply a stripe of cement to the edge of the work by adjustment of its deflector members out of contact with the cement-carrying portions of their respective grooves, or the width of a stripe of cement applied to either or both sides of a work-piece may be varied by rendering inactive one or more of the deflector members.

In order to assist the operator to feed the work to the applying rolls with the edge of the work in alinement with the inner edges of the rolls, a work gage 102 is provided having a tongue formed in a downwardly projecting portion 110 and extending into a slot 104 in the lever 58. The gage 102 is held in adjusted position by means of a screw 106 extending through a slot 108 in the portion 110 and threaded into the lever 58. The work gage 102 is provided with a work-supporting table 112 having an upturned edge portion 114 which serves as a gage for the edge of the work. A holdown finger 116 overhangs the table 112 and acts to prevent the edge of the work from curling as the work is advanced by rotation of the upper and lower rolls.

In the operation of the machine the fluid-carrying roll 54 is lowered from co-operation with the upper fluid-carrying roll 10, the work placed upon the lower roll 54 with its edge in contact with the upstanding edge portion 114 of the gage 102 and the carrier lever and lower roll 54 raised until the upper face of the work is forced against the upper roll 10. The work, gripped between the disks 16 and 72, is advanced by the rotation of the upper and lower rolls and cement applied to one or both sides of the work. When the entire edge of the work has passed beneath the rolls the roll 54 is lowered and the feed stopped in the same manner as the rolls of the machine of Patent No. 1,380,360 referred to above.

Having thus described my invention, what I claim as new and desire to secure by Letters Patent of the United States is:

65 1. A fluid-applying machine having, in combination, fluid-supplying means, a recessed fluid-carrying roll to which a piece of work may be presented and carrying a ribbon of cement in a recess within the outer periphery of the roll, means for holding a piece of work against the outer periphery of said roll, and a deflector located between the roll and the work for plowing fluid from the recess of the roll directly on the adjacent face of the work.

75 2. A fluid-applying machine having, in combi-

nation, fluid-supplying means, a grooved fluid-carrying roll, a member adjustable into and out of a groove to determine the amount of fluid carried thereby, and means for plowing fluid out of the groove and deflecting it into contact with the work. 80

3. A fluid applying machine having, in combination, a tank for fluid having an outlet near the bottom, a fluid-carrying roll located beneath said tank and adapted to engage the upper surface of a work-piece, means for controlling the flow of fluid from the tank to the roll, and scraper means closely adjacent to one another for diverting a large part of the fluid on the roll directly onto the upper surface of the work in adjacent stripes which merge to form a solid ribbon. 90

4. A fluid-applying machine having, in combination, a tank for fluid, a grooved fluid-carrying roll rotatably mounted beneath said tank and arranged to receive fluid therefrom, a slidably mounted member adjustable toward and from said roll to determine the amount of fluid carried thereby, a foot member having an inclined end, said member being adjustable relatively to said roll to engage the fluid carried thereby, and means 100 for holding said foot member in adjusted position.

5. A fluid-applying machine having, in combination, a tank for fluid, a sectional fluid-carrying roll rotatably mounted beneath said tank with the sections carrying individual ribbons of cement, and selective means for deflecting one or more of the ribbons of cement away from said roll and onto the work. 105

6. A cement-applying machine having, in combination, a tank for cement, a grooved cement-carrying roll, a member movable in said groove to determine the thickness of a ribbon of cement to be carried thereby, and means entering said groove for deflecting the ribbon of cement from 115 the groove to the work.

7. A cement-applying machine having, in combination, a tank for cement, a cement roll carrying a ribbon of cement, means for holding a portion of that surface which is to be coated in contact with a portion of said cement roll, a deflector positioned between the axis of the roll and the aforesaid surface of the work to be coated and adjustable substantially radially relatively to said roll to engage the ribbon of cement carried thereby and to push it out directly on to the work, and means for holding the deflector in adjusted position. 120

8. A cement-applying machine having, in combination, a tank for cement, a roll having a plurality of separate means each of which carries a ribbon of cement, means for determining the thicknesses of the ribbons of cement carried by said separate means, and means for deflecting the ribbons of cement from the roll to the work. 130

9. A cement-applying machine having, in combination, cement-supplying means, a sectional cement-carrying roll, said roll comprising a series of thin disks separated by hub members and forming a series of annular grooves for carrying 140 ribbons of cement, deflectors individually adjustable into and out of said grooves for removing cement therefrom and pushing it into contact with the work, and a single member having a series of spaced projections extending into said 145 grooves and adjustable relatively thereto for determining the thicknesses of the ribbons of cement carried in said grooves.

10. A cement-applying machine having, in combination, a sectional cement-carrying roll, 150

- said roll comprising a series of thin disks separated by hub members and forming a series of annular grooves for carrying ribbons of cement by frictional drag, a slide adjustable relatively to said roll to determine the thicknesses of the ribbons of cement carried thereby, and means for deflecting the ribbons of cement from the roll to the work. 80
11. A cement-applying machine having, in combination, a tank for cement, a roll having a plurality of separated adjacent retaining devices each carrying an individual ribbon of cement received from said tank, means for determining the thicknesses of the ribbons of cement carried by said roll, and means selectively adjustable relatively to said roll to plow cement from a fractional portion of said ribbons on the roll directly on to a piece of work. 85
12. A cement-applying machine having, in combination, a tank for cement, a cement-carrying roll rotatably mounted beneath said tank, said roll having a series of annular grooves formed therein for carrying ribbons of cement, said grooves having parallel side walls and a bottom wall disposed at right angles to the side walls, and deflector members having ends dipping in said grooves and independently adjustable substantially radially relatively to said roll to determine the width of a ribbon of cement to be applied to the work. 90
13. A cement-applying machine having, in combination, a tank for cement, a grooved cement roll rotatably mounted directly beneath said tank carrying a plurality of ribbons of cement in said grooves, a single means adjustable relatively to said roll to regulate the thicknesses of all of the ribbons of cement carried thereby, and selective means for deflecting one or more of the ribbons of cement from the roll to the work. 100
14. A double cementing machine having, in combination, an upper cement-carrying roll having a series of closely adjacent grooves, a lower cement-carrying roll, means for supplying cement to said rolls, plow-like deflecting means adjustable toward and away from the grooves of the upper cement-carrying roll to remove cement from some of said grooves and thereby to determine the width of a solid ribbon of cement to be applied to the upper surface of a work-piece, and means adjustable relatively to the lower cement-carrying roll for determining the width of a ribbon of cement to be applied to the under surface of a work-piece. 110
15. A double cementing machine having, in combination, an upper cement-carrying roll, a lower cement-carrying roll, means for supplying cement to said rolls, means adjustable relatively to one roll for determining the width of a ribbon of cement to be applied to one surface of a work-piece, and a plurality of members independently adjustable substantially radially relatively to the other roll thereby cooperatively to determine the width of a composite solid ribbon of cement to be applied to the opposite surface of a work-piece. 120
16. A double cementing machine having, in combination, an upper cement-carrying roll, a lower cement-carrying roll, one of said rolls having a series of closely adjacent grooves, means for supplying cement to said rolls, means adjustable relatively to one roll for determining the width of a ribbon of cement to be applied to one surface of a work-piece, and means adjustable relatively to the grooved roll to deflect cement from a fractional number of adjacent grooves of the roll on to the opposite surface of the work-piece. 125
17. A double cementing machine having, in combination, oppositely disposed superposed cement-carrying rolls, means for supplying cement to said rolls, and means for deflecting ribbons of cement of predetermined widths less than the widths of the rolls from the rolls to the corresponding marginal portions of opposite surfaces of a work-piece, said upper roll having a grooved surface thereby to retain frictionally, without dripping, the fractional portions not deflected. 130
18. A double cementing machine having, in combination, oppositely disposed superposed cement-carrying rolls, means for supplying cement to said rolls, and independently adjustable deflecting means for depositing closely adjacent stripes which merge and form ribbons of variable widths from the rolls to the corresponding marginal portions of opposite surfaces of a work-piece. 135
19. A double cementing machine having, in combination, oppositely disposed cement-applying devices having projecting disks for gripping an interposed piece of work, said devices having cement-regulating means and plow-like cement-deflecting means for pushing ribbons of cement of controllable widths and thicknesses from said devices directly on to the opposite faces of said work-piece, and means for supplying cement to said devices. 140
20. A cement-applying machine having, in combination, a receptacle for cement, a cement-carrying roll rotatably mounted therein and having a smoothly grooved peripheral surface to carry a ribbon of cement and contacting with a piece of work to be coated, a regulator adjustable relatively to said surface to determine the thickness of the ribbon of cement carried thereby, and plow-like means interposed between the bottoms of the grooves and the work for deflecting the entire ribbon of cement from the roll directly on to the work. 145
